UNITED STATES PATENT OFFICE.

JOHN BODENSTAB, OF NEW YORK, N. Y.

DESIGN FOR A KETTLE.

SPECIFICATION forming part of Design No. 23,638, dated September 11, 1894.

Application filed August 9, 1894. Serial No. 519,883. Term of patent 7 years.

To all whom it may concern:

Be it known that I, JOHN BODENSTAB, a citizen of the United States, residing in the city, county, and State of New York, have invented and produced a new and original Design for Pitch-Kettles, of which the following is a specification, reference being had to the accompanying drawings.

Figure 1, is an elevation of a pitch kettle made according to my design; Fig. 2, a plan of the same. Fig. 3, is a central vertical section upon the plane of line 3, 3, Fig. 3.

The leading feature of my design consists in a pitch heating kettle having the shape or

configuration provided, with a compartment within the circular outline of the kettle as shown.

A, is the main body of the kettle which is circular in general contour when taken horizontally, and B, is its interior compartment.

What I claim is—

The design for pitch kettles herein shown and described.

JOHN BODENSTAB.
